PUMP PLUNGER

Sherman H. Holt, Tulsa, Okla.

Application February 22, 1945, Serial No. 579,263.

3 Claims. (Cl. 309—4)

1

This invention relates to oil well pump plungers. In one kind of oil well pump a pump barrel is lowered into a well and locked in position, and a hollow plunger connected to the lower end of a pump rod is reciprocated in the barrel to pump the oil to the surface. In the inverted type pump the lower end of a hollow plunger is locked in the well and a barrel encircling the plunger is reciprocated thereon by means of a pump rod. In either case the plunger has a vertical tubular body surrounded by one or more packing members. One packing member generally is wound around the tube in the form of a coil with one end resting against a stationary member on the tube while the other end engages a packing follower or collar slidably mounted on the tube. On the opposite side of the collar there are one or more packing cups each engaged by a metal cup ring also slidably mounted on the plunger body. The outer ring is engaged by a coil spring which is held in position by a stationary member on the plunger tube. This spring urges the cup rings and packing cups toward the collar which in turn presses against the helical packing coil to keep it expanded against the barrel in which the plunger is mounted. The pressure of the fluid in the well on the packing cups also tends to hold the collar tightly against the packing. On the downstroke of the plunger in an ordinary pump, or on the downstroke of the barrel in an inverted pump, the frictional engagement of the barrel with the packing cups tends to move them and the cups rings and collar away from the helical packing, compressing the spring somewhat in doing so. On the reverse stroke these slideable members all move back to their original positions. This constant travel back and forth tends to create wear on both the packing coil and the packing cups as well as on the spring.

It is among the objects of this invention to provide an oil well pump plunger in which the packing cups and packing follower are restrained from being moved away from the packing coil by friction between the pump barrel and packing cups, and in which this result is accomplished without interfering with the tendency of the plunger spring to keep the packing follower pressed tightly against the packing coil.

The preferred embodiment of this invention is illustrated in the accompanying drawing in which Fig. 1 is a side view, with the barrel and valves partly broken away in section, of an inverted rod pump incorporating my invention, Fig. 2 is an enlarged fragmentary view showing the position of certain plunger elements during a downstroke

2

of the barrel, and Fig. 3 is a vertical section through Fig. 2.

Referring to Fig. 1 of the drawing, a hollow vertical plunger 1 is rigidly mounted on the upper end of a conventional hold-down 2 by which the plunger is held down in an oil well. This hold-down includes an upwardly opening ball check valve 3. Slidably mounted on the plunger is a cylindrical pump barrel 4 which includes at its upper end an upwardly opening ball check valve 5. The top of the barrel is provided with a threaded stud 6 to which the lower end of a reciprocable pump rod (not shown) can be attached for moving the barrel up and down on the stationary plunger. This causes the fluid below the pump to be drawn up through the hold-down and hollow plunger into the barrel, and then to be forced out of the top of the barrel above the upper valve 5.

20 The body of the plunger is a vertical tube 8 (Fig. 2) having an integral enlargement 9 near its lower end and against the bottom of which an annular centering member 10 is held by a coupling 11 screwed part way onto the tube. This coupling is connected by a pipe 12 to the top of bottom valve 3, whereby there is a vertical passage from the lower end of the hold-down to the top of the plunger. Screwed on the upper end of the tube is a pair of nuts 14 and 15 between which 30 there is a centering member 16. The two centering members center the plunger in the barrel.

Mounted on the plunger tube between lower nut 15 and enlargement 9 is the packing by which fluid is prevented from escaping past the outside 35 of the plunger. The main packing consists of a length of suitable packing material wrapped helically in a coil 18 around the plunger tube with its upper end engaging nut 15. The lower end of this coil is engaged by a follower or collar 19 40 slidably mounted on the tube. Engaging the bottom of the collar is a packing cup 20 into which projects the reduced upper end of a metal cup ring 21. The bottom of this ring is engaged by another packing cup 22 into which projects the 45 reduced upper end of another cup ring 23. Both cups and rings are slidably mounted on the plunger tube. Of course, more cups and rings may be used if desired, and some may be located below enlargement 9. Below the lower ring a coil 50 spring 24 is mounted on the tube with its lower end abutting against tube enlargement 9. The purpose of this spring is to hold the packing cups in position and to keep collar 19 pressing upwardly against the packing coil 18 so that the 55 coil will be maintained expanded radially into

contact with the inner surface of the surrounding barrel.

It is the principal feature of this invention that on the downstroke of the barrel on the plunger the friction between the barrel and the packing cups will not move them downwardly on plunger tube 8 and thus cause the packing coil, rings and collar also to work up and down on the tube with resulting wear. Accordingly, a backing ring 26 is slidably mounted on the tube between the upper end of the spring and the lower cup ring, both of which it engages. One of these two adjoining rings 23 and 26 has its surface which is at the end adjacent the other ring inclined to the axis of the tube and to the ring face it engages. Because it is desirable to make the backing ring thin, it is preferred that the lower face 27 of cup ring 23 be inclined or beveled. This ring therefore engages the backing ring only at one side of the plunger tube. This does not keep the spring from performing its function of constantly urging the rings, packing cups, and collar upwardly on the plunger tube. However, on the downstroke of the barrel when its friction against the packing cups attempts to move them downwardly on the plunger tube, lower cup ring 23 is caused to exert pressure on the backing ring at only one side of the tube, whereby the thin ring is canted or cocked on the tube as shown in Fig. 2. The backing ring therefore binds on the tube and refuses to slide downwardly on it. The result is that the packing cups and the other slidably mounted on the plunger tube are prevented from alternately moving down and up on the tube which would cause them to wear an undesirable amount.

According to the provisions of the patent statutes, I have explained the principle and construction of my invention and have illustrated and described what I now consider to represent its best embodiment. However, I desire to have it understood that, within the scope of the appended claims, the invention may be practiced otherwise than as specifically illustrated and described.

I claim:

1. A plunger comprising a vertical tubular body, a packing cup slidably mounted on said body, a cup ring slidably mounted on said body in engagement with said cup, a backing ring slidably mounted on said body in engagement with the cup ring, and a spring mounted on said body and urging said rings toward the cup, one of said rings having its end face which is adjacent the other ring inclined to its axis, whereby any tendency of the packing cup to move the rings axially and compress the spring will cant the backing ring into binding engagement with said body and prevent such movement.

2. A plunger comprising a vertical tubular body, a packing cup slidably mounted on said body, a cup ring slidably mounted on said body in engagement with said cup, a backing ring slidably mounted on said body in engagement with the cup ring, and a spring mounted on said body and urging said rings toward the cup, the cup ring having its end face which is adjacent the backing ring inclined to the backing ring face that it engages, whereby any tendency of the packing cup to move the rings axially and compress the spring will cant the backing ring into binding engagement with said body and prevent such movement.

3. A plunger comprising a vertical tube, a helical packing member wound on said tube, means rigidly mounted on said tube against one end of said packing, a collar slidably mounted on said tube against the other end of said packing, a packing cup slidably mounted on said tube on the other side of said collar, a cup ring slidably mounted on said tube in engagement with said cup, a thin backing ring slidably mounted on said tube in engagement with the cup ring, and a coil spring mounted on said tube and urging said rings and cup toward said collar, the cup ring having its end face which is adjacent the backing ring inclined to its axis, whereby any tendency of the packing cup to move the rings axially and compress the spring will cant the backing ring into binding engagement with said body and prevent such movement.

SHERMAN H. HOLT.
